UNITED STATES PATENT OFFICE.

STEPHEN F. BRIGGS AND EDWARD N. JACOBI, OF MILWAUKEE, WISCONSIN, AS-
SIGNORS, BY MESNE ASSIGNMENTS, TO BRIGGS & STRATTON CORPORATION, OF
MILWAUKEE, WISCONSIN, A CORPORATION OF DELAWARE.

LATCH SWITCH.

Application filed October 15, 1920. Serial No. 417,078.

This invention relates to switches for controlling electrical circuits and while it has to do with that type of switches known as lock switches, it is designated a latch switch because it has for its object to provide for locking by means of a movement of the switch itself to a predetermined locking or latching position, thus permitting normal movement of the switch from one position to another until it is moved to the locking position, whereupon it is locked and a key or other means is required for unlocking it to enable it to be moved from that position.

Though the invention is not restricted to any particular use, it is well adapted for the controlling of lighting and ignition circuits of automobiles wherein it is desired that tampering with the switch should be prevented, both to avoid a change in the lighting condition, which may render the owner liable to a fine, and to prevent theft of the automobile. Particularly it is desired by means of such a switch to enable the lighting switch to be moved to a desired position where it will be automatically locked incident to the locking of the ignition switch as with one form of the invention, or the ignition switch is locked as with another form thereof.

Another object of the invention is to simplify the construction of the switch mechanism and the lock mechanism so as to minimize the cost of manufacture thereof.

With the above and other objects in view the invention consists in the latch switch as herein claimed and all equivalents.

Referring to the accompanying drawings in which like characters of reference indicate the same parts in different views:

Fig. 1 is a front view of the switch panel provided with a latch switch forming one embodiment of this invention for controlling automobile lighting and ignition circuits;

Fig. 2 is a rear view thereof;

Fig. 3 is a vertical sectional view thereof;

Fig. 4 is a rear view with the terminal head removed and the switch locked;

Fig. 5 is a similar view with parts sectioned;

Fig. 6 is a front view with the panel removed and the switch levers sectioned and unlocked;

Fig. 7 is a face view of the terminal head;

Fig. 8 is a central sectional view of the switch on line 8—8 of Fig. 2;

Fig. 9 is a sectional view on line 9—9 of Fig. 5, with the switch mechanism removed;

Fig. 10 is a rear view of the lighting switch spider and its associated parts;

Fig. 11 is a perspective view of the lock pawl and its associated parts;

Fig. 12 is a sectional view showing the switch levers in position in which they are capable of movement though the lock pawl is under spring pressure;

Fig. 13 is a similar view showing the lock pawl engaging and locking both switch levers as a result of the movement of the ignition switch lever from the position shown in Fig. 12;

Fig. 14 is a sectional view showing the ignition contact arm in the locking position of the ignition switch lever and showing the lock barrel and the engagement of its tumblers with its sleeve for holding the lock pawl spring under tension;

Fig. 15 is a perspective view of the ignition contact arm;

Fig. 16 is a perspective view of the lighting thrust cup;

Fig. 17 is a perspective view of the ignition thrust cup;

Fig. 18 is a sectional view of a modification.

In these drawings 20 indicates a front plate or panel on which the switch of this invention is mounted and by means of which it is adapted to be attached to the dash or instrument board of an automobile for controlling the lighting and ignition circuits.

As seen in Fig. 1, the ignition switch lever 21 and the lighting switch lever 22 are concentrically mounted in the front plate, the latter having a number of positions indicated by marks on the front plate for establishing the different lighting circuits, and the former having likewise different positions marked on the front plate, one of which is a locking position. Beneath the switch levers a key-controlled lock barrel 23 is mounted in the front plate for cooperating with the ignition switch lever in effecting a locking of both switch levers.

On the back of the front plate 20 is secured by means of rivets 24 a flanged cylindrical switch case 25, forming a housing surrounding the switch and lock parts, and an insulating terminal head 26 with notches receiving lugs 27 of the switch case forms a cover plate

for the switch case. In order to secure the terminal head in place screws 28 pass therethrough and are threaded into an arc-shaped tapped bracket 29 mounted on legs which 5 turn outwardly and are confined between the back of the front plate and the flange of the switch case 25 in depressions 30 formed in the latter.

Lugs 31 forced up from the ends of the 10 legs of bracket 29 enter openings in the flange of the switch case, as seen in Fig. 8, to securely lock the bracket in place. Because of the length of the legs the bracket is spaced from the front plate where it may be 15 conveniently reached by the screws 28 and where it will be out of the way of moving parts.

The ignition lever 21 forms a cup-shaped bearing 32 for the lighting switch lever 22, 20 while it in turn has a bearing in the front plate. The lighting switch lever 22 has a short stem 33 constituting an integral projection therefrom and passing through the bottom of the cup-shaped bearing 32 of the 25 ignition lever 21, and a screw 34 embedded within it during the casting operation forms a central projecting screw stud by means of which the lighting switch member is secured to the stem.

30 A cup-shaped thrust cup 35, shown in Fig. 16, has its outwardly turned flange bearing against the back of the front plate, except where lugs 36 stand up and these lugs enter openings in the front plate to keep the thrust 35 plate from turning. As the thrust cup is held in its engagement with the front plate by the pressure of the lighting switch, as will later appear, it is stationary. The portion of the lighting switch stem 33 which passes through 40 the center of the lighting thrust cup 35 is provided with opposite flat faces to form a driving connection for the lighting switch member which is mounted thereon. An insulating plate 37 and a corresponding metal plate 38 have openings shaped to fit upon the 45 flat sides of the lighting switch stem and against the shoulders formed at the end of the flat sides, the metal plate being in bearing contact with the flat surface of the lighting thrust cup 35. A switch spider 39, preferably of duplicate stampings and forming radially and downwardly extending spring arms, is secured to the insulating plate 37 by means of a spider driving plate 40, which 50 consists of a ring having lugs bent from the edge thereof and passing through notches in the edges of the spider and the insulating plate to tie them together and compel the spider to be driven by the lighting switch 55 stem. The openings in the spider and the spider driving plate are considerably larger than the screw stud 34 so as to avoid grounding contact therewith. An insulating washer 41 and a metal washer and a centering cup 42 60 are fitted on the screw stud 34 and a nut 43

threaded on said screw stud and contained within the centering cup clamps the parts together. In practice a drop of solder is placed over the end of the nut and the screw stud to keep the nut from backing off. It will be seen 70 that the lighting switch lever is rotatably mounted and carries with it the lighting switch spider which is insulated therefrom and the contact arms of the spider bear with spring pressure against the terminal head and engage lighting contact studs 44 thereof, the thrust of the spring action of the contact spider being taken by the metal disk 38 bearing on the stationary lighting thrust cup 35 and the movements being limited by the engagement of shoulders 45 of the insulating disk with stop lugs 46 raised from the surface 80 of the lighting thrust cup.

An ignition thrust cup 45, shown in Fig. 17, fits over the end of the cup-shaped bearing of the ignition switch lever 21 and is secured thereto by means of screws 46 which are threaded in nuts 47 contained in square pockets in the recess of said cup-shaped portion of the ignition lever 21. The edge of the ignition thrust cup 45 bears against the inner face of the front plate to prevent the withdrawal of the ignition lever and to take the thrust of the ignition spring, as will later appear. An angularly bent arm 48 projects from the ignition thrust cup 45 and passes through a sector-shaped opening in the lighting thrust cup 35 and has a headed stud 49 riveted thereto. A washer 50 and a coil spring 51 are mounted on the stud, the spring serving to force the washer toward the head of the stud. An ignition contact arm, shown in Fig. 15, is rotatably mounted on the centering cup 42 and is driven by the stud 49 of the ignition thrust cup so as to respond to movements of the ignition lever 21. This ignition contact arm consists of a plate of insulating material 52 with a metal plate 53 secured thereto by having tangs at its ends passed through the insulating plate 52 and bent over thereon. The tangs of the metal contact plate 53 are not as wide as the upturned ends of said plate from which they project and consequently said plate is spaced from the insulating plate 52 in the manner clearly shown in Fig. 8, and the insulating plate 52 may fit upon the centering cup 42 without a grounding contact of the contact plate 53 therewith. The head of the stud 49 is elongated and an elongated opening in the insulating plate 52 is adapted to pass over the head of the stud but the opening in the insulating plate extends lengthwise thereof, whereas the direction of elongation of the head of the stud is such that it will be at right angles to said opening when the contact arm is assembled, as shown in Fig. 4. Thus, in assembling, the contact arm is positioned to receive the elongated head of the stud and forced thereon against the pressure of spring 100 105 110 115 120 125 130

51 and is then turned and rocked on the stud to fit on the centering cup. Opposite the elongated opening of insulating plate 52, the metal plate 53 is provided with an opening 54 to avoid grounding contact with the stud 49 and the edges of the metal plate on either side of this opening are turned down to form strengthening flanges bearing on the insulating plate. At the axis of rotation and at its 10 outer end the contact plate 53 is depressed to form rounding contacts engaging respectively a central terminal stud 55 and an ignition stud 56. As the pressure of spring 51 is applied to the ignition contact arm between its 15 points of contact, both points of contact are held firmly in engagement with the terminal head or its studs. The range of movement of the ignition lever is determined by the engagement of arm 48 of the ignition 20 thrust cup with the sides of the sector-shaped opening in the stationary lighting thrust cup but this movement is sufficient to carry the ignition contact arm over the three positions marked on the front plate. In the "on" position it is held by the contact projection fitting 25 in a recess in the end of ignition terminal stud 56 and in the other positions it is held by said projection fitting in recesses 57 in the terminal head.

30 The lock barrel 23 has a reduced neck portion fitting within a flanged escutcheon ring 58 which passes through the opening in the front plate with its flange bearing against the back of the front plate, as best seen in Fig. 9.

35 The shoulder formed by the reduced portion of the lock barrel 23 is spaced from the flange of escutcheon ring 58 and in this space is fitted a lock pawl 59 and a lock spring driver 60, as shown in Fig. 11.

40 The lock pawl 59 consists of a sheet metal plate having a notch fitting approximately two-thirds of the way around the reduced neck portion of the lock barrel 23. The ends of this notched portion form shoulders, one 45 of which is engaged by a hook 61 on the end of the lock spring driver 60 for withdrawing the lock pawl from its locking position, as will later appear. One end of the lock pawl 59 forms an outwardly extending hook-like 50 arm bent to a plane parallel with the plane of the main portion of the lock pawl, with its outer edge bent back to form an arc-shaped locking flange 62. The other end of the lock pawl 59 extends outwardly to form a spring 55 supporting arm 63, its extremity being bent to a plane at approximately right angles with the plane of the main portion of the lock pawl and having one or more leaf springs 64 riveted thereto. The edge of this bent portion 60 of the arm to which the spring is riveted is slightly raised to form a bead against which the end of the spring engages to prevent the spring from swinging on the rivet. A reinforcing plate 65 of very thin sheet 65 metal is mounted on the upper face of the lock

pawl as it is viewed in Fig. 9; and this plate is of the shape shown in Fig. 6 with tangs 66 bent up from its edges and around the edges of the lock pawl and embedded therein. This reinforcing plate 65 has an opening concentric with the notch of the lock pawl and of a diameter to receive within it the outwardly extending flange of the escutcheon ring 58, as seen in Fig. 9.

The lock spring driver 60 is also a sheet metal stamping of a general arc-shape and fitting around the reduced neck portion of the lock barrel 23 and against the shoulder thereof. It, however, extends around the reduced portion of the lock barrel for a greater distance than the lock pawl 59 and besides the hook 61 at one end thereof for engaging the shoulder of lock pawl 59, as before mentioned, its other end is provided with a hook portion or angularly bent projection 67, one part of which is engaged by the end of spring 64 and another part is engaged by a pin 68 projecting from the reduced neck portion of the lock barrel 23. This pin 68 travels between the two projections 61 and 67 of the lock spring driver 60 and is the means for turning the lock spring driver and the lock pawl. A projection 69 bent out from the lock spring driver 60 is adapted to engage the wall of the switch case beyond the pocket thereof in which the bend of the lock pawl is contained to form a stop, as shown in Fig. 5.

The lock barrel 23 is surrounded by a cylindrical sleeve 70 which has a flange at one end forming ears through which screws 71 pass 100 and are threaded into a sector-shaped portion 72 bent over from the edge of the switch case. The portion 72, besides having the opening to receive the lock sleeve 70, has a finger 73 bent from its edge and lying parallel 105 with the wall of the switch case. The lock sleeve 70 has opposite openings to receive the ends of tumbler slides 74 which are fitted in transverse openings through the lock barrel 23. When the key 75 is inserted in the key 110 slot of the lock barrel 23 its serrated edges serve to withdraw the tumbler slides, so that the lock barrel may be turned by means of the key. The key may not be removed until the lock barrel is returned to the position in which 115 the tumblers may project in the openings of the lock sleeve, for in any other position the tumblers are prevented by the lock sleeve from moving to accommodate the passage of the key. When the key is removed and the tumbler slides project into the openings of the lock sleeve they are prevented from working out through said openings by the finger 73 and the wall of the switch case, as will be 120 seen in Fig. 14. The lock pawl 59 is capable 125 of a rocking movement around the lock barrel 23, and its hook-shaped pawl member 62 is adapted to engage and lock both of the switch levers. The lighting thrust cup 35 has an opening in its side wall and a projection 76 130

leading therefrom forms a guard against which the face of the pawl member 62 bears to guide said pawl member through the opening and into an opening 77 in the side of the 5 ignition thrust cup and an opening 78 in the ignition lever and into an opening formed between or on either side of a pair of locking lugs 79 on the lighting switch lever, as seen in Fig. 13. It is only the flanged portion of 10 the pawl member 62 which enters the openings in the switch levers, the face portion thereof being accommodated between the lighting thrust cup 35 and the ignition thrust cup 45. When so engaged by the lock pawl the 15 switch levers are incapable of movement.

In operation both switch levers are free to be moved to their various positions as long as the lock pawl 62 is withdrawn from its locking position and is not under spring pressure, 20 which condition is shown in Fig. 6. As it is placed in this condition by the turning of the key to a horizontal position, in which the key cannot be removed, the presence of the key indicates the existence of the unlocked condition. 25 If it is desired to lock the switch, the ignition switch is moved to the lock position and the key is turned to its vertical position from which it can be removed. The turning of the key to this position moves the lock 30 pawl from the position shown in Fig. 6 to the position shown in Fig. 5, the turning of the lock barrel causing the pin 68 to engage the lug 67 of the lock spring driver and force it to turn so that its pressure against the spring 35 64 compels the lock pawl to turn with it. The pawl member 62 finds the openings of the switch levers in position to receive it so that the ignition switch is locked in its off position and the lighting switch is locked in any position 40 in which it may be at that time. On unlocking the switch by inserting the key and turning it in the opposite direction, the pin 68 is turned against the lug 61 of the lock spring driver and it in turn is moved against 45 the shoulder of the lock pawl to force the lock pawl out of its locking engagement with the switch levers, so that it is returned from the position of Fig. 5 to the position of Fig. 6 and both switches are again free to be operated. 50 If the ignition switch lever is not in the lock position when the key is turned to the vertical position and withdrawn, the lock pawl is incapable of completing its throw and the movement of the lock spring driver only 55 serves to bend the spring 64 and so place it under tension. This is the position of the parts shown in Fig. 12 and as the tumbler slides by their engagement with the openings in the lock sleeve hold the lock barrel against 60 turning, the lock pawl will remain under spring pressure until the ignition switch lever is moved to the lock position. The ignition switch lever may be moved to the lock position at any time after the key has been 65 so removed and thereupon the lock pawl

snaps into engagement with both switch levers, as shown in Fig. 13, again locking the ignition switch in the off position and the lighting switch in any position in which it may have been placed at that time.

It will be understood that with a switch constructed in accordance with this invention the lock may be set to operate as a latch when the ignition switch is later moved to the lock position and this enables the owner who finds it inconvenient to personally attend to the lighting and the locking of the automobile to send a messenger for that purpose without having to entrust him with the key. The messenger will first move the lighting switch lever as directed and will then swing the ignition switch lever to the lock position, whereupon both levers become automatically locked.

Instead of the lighting switch lever being capable of being locked in any of its positions, it may be preferred to construct it so that it will be capable of being locked only in the dim position. To do this it is only necessary to broaden the lugs 79 of the lighting switch lever as shown in Fig. 18 so that the locking pawl is blocked thereby in either the off or the bright position of the lighting switch lever and can only serve as a lighting switch lock by entering the opening between them in the dim position. With this construction there is a double latch operation for the lock pawl. It can first spring into locking engagement with the ignition switch lever when said lever is moved to the lock position and later it may spring into engagement with the opening between the locking lugs 79 of the lighting switch lever when said lever is moved to the dim position. The switch may thus have the ignition locked by the owner when he leaves the car and may later be changed by the messenger from either off or bright position to dim position of the lighting switch lever, but as soon as the dim position is reached the lock is effective and no further change can be made. The double latching function of the lock pawl permits first the automatic locking of the ignition switch and later the automatic locking of the lighting switch.

The terminal studs, as usual, constitute binding posts to facilitate the making of wiring connections, as indicated by the names appearing near them on the back of the terminal head, so that the different connections are established for the different positions of both switch levers and certain economies are effected by arranging the contacts of both switches in the same circle and utilizing the equalized ignition contact arm in conjunction with the lighting switch spider.

If it is only desired to lock the ignition switch, the end of the lock pawl flange 62 which engages the lighting switch lever may

be cut away so that the lighting switch may be changed as desired even when the switch is locked.

We desire it to be understood that this invention is not limited to any specific form or arrangement of parts except in so far as such limitations are specified in the claims.

What we claim as new and desire to secure by Letters Patent is:

10. 1. In an electrical switch, a pair of switch members having operative positions and one of them having a locking position, and means for locking both switch members automatically when the said switch member is moved 15 to the locking position.

2. In an automobile switch, a lighting switch member having different operative positions, an ignition switch member having different operative positions and a locking 20 position, and a key controlled locking mechanism locking both of the switch members when the ignition switch member is moved to the locking position.

3. In an electrical switch, a switch member having operative positions and a locking 25 position, a pawl capable of engaging the switch member in its locking position, and key operated lock means for giving bias to the pawl in a direction to effect its locking engagement with the switch member when the switch member is moved to the locking position.

35. 4. In an electrical switch, a switch member having operative positions and a locking position, a pawl for engaging the switch member in the locking position, a spring for operating the pawl, and key controlled lock means for placing the spring under tension.

5. In an electrical switch, a switch member having a locking position, a rotatably mounted key operated lock barrel, a pawl pivotally mounted on the lock barrel for engaging the switch member in its locking position, a spring on the pawl, a spring driver 45 rotatably mounted on the lock barrel engaging the spring and the pawl, and a projection on the lock barrel for engaging the spring driver for placing the spring under tension to move the pawl into engagement 50 with the switch member when turned in one direction and for moving the pawl out of engagement with the switch member when turned in the other direction.

55. 6. In an electrical switch, a switch case having a front plate, a switch lever having a stem, a second switch lever fitting around the stem as a sleeve and fitting within the front plate, a thrust member secured to the sleeve and bearing on the front plate, a spring actuated contact member carried by the sleeve, a second thrust member secured to the front plate, a spring actuated contact member mounted on the stem and bearing on the second thrust member, and a terminal head for 60 the casing engaged by the switch members.

7. In an electrical switch, a switch case having a front plate, a switch lever having a stem, a second switch lever fitting around the stem as a sleeve and fitting within the front plate, a thrust member bearing on the 70 front plate, a switch member mounted on the stem and bearing on the thrust member and provided with spring actuated contact fingers, a spring pressed contact arm rotatably fitting on the stem and having driving connection with the sleeve, and a terminal head on the switch case having contacts engaged by the contact fingers and the contact arm.

8. In an electrical switch, a pivotally mounted switch member, contacts on the 80 switch member at the pivotal axis and distant therefrom, spring means bearing on the switch member between the contacts, and fixed contacts engaged by the contacts of the switch member.

9. In a switch, a pivotally mounted switch member, contacts thereon at the pivotal axis and distant therefrom, a driving means having connection with the switch member between the contacts, a spring on the driving 90 means bearing on the switch member, and stationary contacts engaged by the contacts of the switch member.

10. In a switch, a guide; a switch member pivotally mounted on a centering member, 95 contacts on the switch member near the pivotal axis and distant therefrom, a rotatably mounted driving means for the switch member having connection with the switch member between the contacts, said driving means 100 consisting of a pin having an elongated head and fitting on an elongated slot of the switch member and crossed therewith, a spring on the pin bearing on the switch member, and stationary contacts engaged by the contacts of the switch member.

11. In a switch, a casing having a front plate, a switch lever having a stem, a second switch lever fitting on the stem as a sleeve and fitting in the front plate, a thrust cup secured to the front plate with the stem passing therethrough, a second thrust cup secured to the sleeve and bearing on the front plate and provided with an arm extending through the first thrust cup, a switch member mounted on the stem and bearing on the first mentioned thrust cup and provided with spring contact fingers, a centering member on the stem, a switch member pivotally mounted on the centering member and provided with contacts and having driving connection with the arm, and a terminal head on the switch case having contacts engaged by the contacts of the switch members.

12. In a switch, a rotatably mounted switch lever, a pivotally mounted pawl adapted to engage the switch lever in one position thereof to prevent it from turning, a rotatably mounted lock barrel, a spring on the pawl, a spring driver mounted on the lock 125 130

barrel and having means for engaging the spring when turned in one direction and for engaging the pawl when turned in the other direction, a pin on the lock barrel for engaging the spring driver, and key operated tumblers in the lock barrel for holding the lock barrel in the position in which the spring is engaged by the spring driver for forcing the pawl into engagement with the switch lever when the switch lever is in position therefor.

13. In a switch, a switch case, a switch lever mounted therein, a pivotally mounted pawl for engaging the switch lever in one position thereof, a spring on the pawl, a lock barrel, a spring driver mounted on the lock barrel and having means for engaging the spring and the pawl, a projection on the lock barrel engaging the spring driver, key controlled tumblers in the lock barrel for holding it in the position in which the spring is engaged for forcing the pawl into engagement with the switch lever, and a projection on the spring driver for engaging the switch case in such position of the lock barrel.

14. In a switch, a pair of switch levers, one mounted within the other and both provided with registering openings, and a key controlled spring pressed swinging pawl adapted to engage said openings for locking both switch levers.

15. In an electrical switch, a switch member, a second switch member having opera-

tive positions in one of which it may be locked, and spring-latch locking means for said switch members effective upon the first switch member but not effective upon the second switch member until it is in said position.

16. In an electrical switch, a pair of concentric switch members, and spring-latch locking means for the one switch member requiring a predetermined operative position of both switch members.

17. In an electrical switch, a switch member, a second switch member, spring-latch locking means for the first switch member for locking it independently, and locking means for the second switch member dependent upon the locking of the first switch member.

18. In a switch, a pair of switch levers, one mounted within the other and both provided with registering openings, and a key-controlled spring-pressed swinging pawl adapted to engage one of said openings for locking one switch lever and adapted to spring into the other of said openings for locking the other switch lever when the latter is moved into position to cause the openings to register.

In testimony whereof, we affix our signatures.

STEPHEN F. BRIGGS.
EDWARD N. JACOBI.
